M. B. BAIRD AND G. A. WALLS,
SANITARY DRINKING CUP,
APPLICATION FILED DEC. 26, 1919.

1,378,310.

Patented May 17, 1921.

UNITED STATES PATENT OFFICE.

MELVILLE B. BAIRD AND GEORGE A. WALLS, OF KANSAS CITY, MISSOURI; SAID WALLS ASSIGNOR, BY MESNE ASSIGNMENTS, OF HIS RIGHT TO J. C. W. BLAND, OF TULSA, OKLAHOMA.

SANITARY DRINKING-CUP.

1,378,310.

Specification of Letters Patent. Patented May 17, 1921.

Application filed December 26, 1919. Serial No. 347,312.

To all whom it may concern:

Be it known that we, MELVILLE B. BAIRD, and GEORGE A. WALLS, citizens of the United States, residing at Kansas City, in the county of Jackson and State of Missouri, have invented certain new and useful Improvements in Sanitary Drinking-Cups; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a drinking cup of the type known as the sanitary drinking cup, usually found in containers at public fountains and the like.

One of the objects of the invention is to construct a simple and efficient cup formed from a single sheet of material and normally flat in the form of an envelop so that the cups may be easily arranged in stacks and introduced into receptacles from which they may be vended or ejected upon the operation of certain mechanism or withdrawn from the machine, as will be well understood.

In the drawings,

Figure I is a perspective view of a cup constructed in accordance with the present invention.

Fig. II is a vertical, sectional view through the cup.

Fig. III is a cross sectional view illustrating the folds for reinforcing the joined walls, and

Fig. IV is a perspective view of a blank, showing the sheet prior to being folded into cup form.

Referring now to the drawings by numbers of reference:

1 designates a blank, Fig. IV, adapted to be folded along the lines 2-2' to join the side edges of the blank together to form a tube and adapted to be folded along the transverse lines 3-3' to close the bottom and provide a reinforcing lip-engaging edge respectively. The lines 2-2' and 3-3' in close or bound the central body portion 4 and the lines 2-2' divide the body portion 4 from the side flaps 5 and 6 having curved cut-out portions 7-7' so that when the blank is folded into cup form, the mouth

opening 14 will be provided by bending the adhesive facing flap 11 back upon the body portion 4 and sealing it thereto. The ends of the side flaps 5 and 6 are inclined and are adapted to be bent back upon themselves along the lines 9 and 10, the flap 6 being provided with adhesive material so that it can be pasted against the outer face of the flap 5 when the flaps 5 and 6 are folded together, as shown in Fig. III. The ends of the flaps 5 and 6, which are folded back upon themselves, will, in conjunction with the adhesive-faced flap 12, entirely close the bottom of the cup so that danger of leakage will be avoided. When the flap 12 is pasted across the flaps 5 and 6, the over-turned edges 9 and 10 will partake of the form shown in Fig. II so that a double seal will be provided; that is, a seal formed by the roll caused by turning the ends of the flaps 5 and 6 over against themselves and by the sealing flap 12.

It will be observed that the adhesive material 12 does not extend entirely to the free end of the flap but that there is a strip 13 devoid of adhesive material so that the tip of the flap 12 may be turned outwardly, as shown in Figs. I and II. This outwardly turned lip or tip 13 enables the envelop to be engaged by an ejector, as it lies flat in the stack so that it may be readily removed from its stack and projected through a slot in the wall of the vending machine in a well known manner.

By reference to Figs. I and III, it will be observed that the flaps 5 and 6 have relatively wide over-lapping portions so that when they are secured together, the cup will be materially reinforced and that a relatively stiff central reinforcing portion will be formed; therefore, there will be no danger of the cup crumpling when it is being removed from the machine.

It will also be observed that the over-turned reinforcing edge formed by the flap 11 will present a rounded appearance to the drinking edge of the cup so that liability of the lips becoming abraded by rough edges of the cup will be eliminated.

What we claim and desire to secure by Letters Patent is:

1. A drinking cup blank comprising a rectangular body portion, side flaps on the body portion having cutout, curved portions

at one end of each and each flap having an inclined extension folded back upon the main flaps to form parts of a bottom for said cup, a flap at one end of the blank, 5 foldable back upon the blank to form a reinforcing lip-engaging edge, and a flap at the other end of the blank foldable over the side flaps and over the bent-up ends thereof, the last named flap having adhesive material 10 over the major portion thereof with an end strip devoid of adhesive material whereby the end in the finished cup may be curled outwardly to form an engaging portion.

2. A drinking cup comprising a flexible 15 receptacle, the walls of which normally lie

one against the other, one end wall having a reinforcing, lip-engaging portion, the walls being reinforced at their point of connection, and a bottom member having a free, out-turned ejector-engageable end.

3. A drinking cup comprising a flexible receptacle consisting of a tube having an end-closing flap to provide a bottom, the end-closing flap having an out-turned edge for engagement with an ejector.

In testimony whereof we affix our signatures.

MELVILLE B. BAIRD,
GEORGE A. WALLS.
